UNITED STATES PATENT OFFICE.

ANTHONY M. ZOTTOLI, OF QUINCY, MASSACHUSETTS.

METHOD OF AND APPARATUS FOR MAKING CEMENT BRICKS AND THE LIKE.

Application filed October 10, 1924. Serial No. 742,773.

To all whom it may concern:

Be it known that I, ANTHONY M. ZOTTOLI, a citizen of the United States, residing at Quincy, county of Norfolk, State of Massachusetts, have invented a certain new and useful Improvement in Methods of and Apparatus for Making Cement Bricks and the like, of which the following is a specification, reference being had therein to the accompanying drawings.

The invention relates to a new and useful improvement in method of and apparatus for making bricks and the like out of cement. The object of the invention is to provide a simple and compact apparatus whereby a plurality of bricks or the like may be made at the same time out of a large mass of cement instead of molding each block separately.

One feature of the invention consists in providing a box into which a mass of cement may be poured while in a soft condition and providing a movable splitting member or members, each carrying a partition member which may be drawn through the bed of soft cement in the box in such manner that the partition member will divide the mass into layers. Another feature consists in forming the partition member of sheet material of such a character that it may be readily severed and providing means for cutting down through several layers and partition members before the cement becomes set so that each layer may be divided into a plurality of blocks. Other features of the invention will be fully described as set forth in the claims hereinafter.

The invention will be fully understood from the following description when taken in connection with the accompanying drawings, and the novel features thereof will be pointed out and clearly defined in the claims at the close of this specification.

In the drawings:

Fig. 1 is an isometric view of the box member of the apparatus which receives the bed of cement.

Fig. 2 is a section on line 2—2, Fig. 1.

Fig. 3 is an isometric view of the base member which cooperates with the box.

Fig. 4 is an isometric view of one of the

splitting members with one of the movable partition members attached thereto.

Fig. 5 is a fragmentary sectional view of one of the vertical walls showing one of the grooves in which the sliding splitting member moves.

Fig. 6 is a vertical sectional view longitudinally through the box after the box has been filled with cement, the movable splitting members being mounted in the box in their guideways and the movable partition members attached to the rear ends of the splitting members before being drawn into the box.

Fig. 7 is a transverse sectional view showing parts in the position shown in Fig. 6.

Fig. 8 is a sectional view on the same line as Fig. 6, the base member being partly broken away, showing the splitting members pulled through the box and the movable partition members moved into operative position.

Fig. 9 is a longitudinal sectional view on the same line as Figs. 6 and 8 showing the parts after the box member has been pulled down into telescoping relation to the base member and leaving the set of formed bricks in different layers superimposed upon each other and all resting on the base member.

Referring to the drawings:

A represents the box member and B the base member. The box A is open at the top and bottom. It has two side walls 1, 1 and two end walls 2, 2, the two side walls being preferably without openings, that is, without any crevices or open spaces through which the cement would ooze out. The two end walls 2, 2 are formed with horizontal slits 3, 3, the number of such slits depending upon the number of layers into which it is intended to divide the mass of cement. The horizontal slits in one end are in alignment with the slits in the opposite end, said slits being openings through which the horizontal movable splitting members herein-after described are drawn to split the mass of cement into layers.

Preferably the box is provided with a plurality of vertical partitions 5, as many as desired, thus dividing the interior of the box into a plurality of longitudinal com-

2

partments each of which is of the width of the individual bricks in the finished form. The box may be only of the width of a single brick and still embody the invention 5 but it is intended to have the box made with a plurality of vertical partitions dividing it into a number of compartments in order to increase the capacity of the apparatus. The number of compartments thus formed may 10 be as many as desired according to the capacity desired and also the number of horizontal slits for the movable splitting members may be made as many as desired for the same reason.

15 The vertical partitions 5 are preferably permanently fastened to the walls, although this is not necessary provided they are rigidly maintained in position during the use of the apparatus.

20 The two side walls 1, 1 are each formed with a longitudinal groove or guideway 6 on the inner face thereof in alignment with the slits 3 in the end walls and each of the partition members 5 is formed on each of its 25 two faces with similar grooves or guideways also in alignment with said slits.

25 A movable splitting member 7 is slidably mounted in each pair of guideways 6 in each compartment of the box. Said splitting member is preferably made of a thin strip of metal having a cut-out interior 8 leaving only enough metal at the two sides to fit in the grooved guideways 6 in the two side walls of the compartment. A cross piece 9 30 at the forward end extends out through the front end of the box and serves as a handle for operating the splitting member. The rear end has a cross portion 10, which serves as a knife, the front edge 11 of which cuts 35 the way through the mass of cement. Preferably the guideways 6 are V-shaped and the outside edges of the splitting member are bevelled to fit into said guideways. The grooves and engaging edges of the splitting 40 member are thus formed for the purpose of preventing the cement from collecting in the grooves during the operation of the apparatus.

45 A strip of sheet material 12 is fastened to the rear end of said splitting member and extends rearwardly as shown in Fig. 6, when the splitting member is in its normal position while the box is being filled with cement and before the operation of the splitting into layers. This sheet material should be in the form of a strip of the same width as the compartment. It should be of material which can be readily cut by the vertically movable knives to be hereinafter described and preferably should be made of material which will not adhere to the cement even when the cement is in its softest condition. A very good material for this purpose is oil paper. It may come in a roll 50 of many yards and be drawn from the roll

as desired by drawing the movable splitting member through the box. It is not deemed necessary to show the roll in the drawings as it will be readily understood how this may be done.

70 Mounted in the top of the box A are a plurality of knives 13 which extend transversely of the box and fit into transverse grooves 14 in the side walls 1 and partition members 5, as shown in Fig. 1.

75 The base member B has a bottom member 15 on which are mounted a plurality of vertical standards 16 corresponding in number with the compartments of the box and on top of each of these standards are mounted a series of rails or blocks 17, each of which is of a width equal to the interior width of one of the longitudinal compartments of the box A. Spaces 18 between the several rails or blocks 17 are equal to the 80 thickness of the vertical partition members 5 of the box and the outside width of the space occupied by all of the rails or block members 17 when mounted on said standards 16 and the outside length of said rail or block members will be such that when the box is mounted upon the top of said member B, it may, at the proper time, be telescoped down onto the base member by engaging the longitudinal partition members 5, 5 in said 85 spaces 18 between the block members and pressing down on the box member.

90 In order to support the box member on the base until such time as it is to be pushed down, there are provided suitable supporting means which are releasable to permit the telescoping. The means shown in the drawings consists of pins or dowels 19 projecting from the outside faces of the two outside rail members 18, as shown in Figs. 3, 6 and 7. These pins may be pulled out when it is 95 desired to let the box down. It is to be understood that any other suitable supporting means may be employed.

100 The said rail members 17 are preferably mounted on the top of the standards 16 in such manner that they are readily removable therefrom for the purpose of transferring the load of bricks resting thereon at the completion of the operation of forming the 105 bricks as will be hereinafter described. Any suitable form of construction which will permit such separable mounting of the rails may be employed. As shown in the drawings, the rails are formed with longitudinal grooves 20 and the standards are formed with longitudinal tongues 21 to permit a tongue and groove engagement of the rails with the standards. This will prevent the sidewise displacement of the rails 110 and keep them properly spaced apart from each other. The operative may very readily center them longitudinally on the standards. The said rail members 17 are formed with 115 transverse grooves 22 so located as to be in 120 125 130

alinement with the knives 13 when the box is telescoped onto the base. The top of each rail member is thus divided into sections substantially of the same surface dimensions 5 as the face of one of the bricks.

In operation the box A will be positioned on the base member B with the lower edge of the side wall 1, 1 resting on the pins 19 or whatever other supports may be used and 10 so centered that the vertical partition members 5 will be in alinement with the spaces 18 between the rails or block 17, as shown in Fig. 7, and so that the end walls 2, 2 will be centered with relation to the ends of 15 the blocks or rails 17, as shown in Fig. 6. The cement which has been previously prepared of the proper consistency will then be poured into the different compartments of the box, filling them all, as shown in 20 Figs. 6 and 7. Each compartment is open and unobstructed for its full depth to receive the cement as the side members of the splitting member 7 are wholly within the guide grooves as already explained. Now 25 while the mass of cement is still soft and before it begins to set, the handle 9 of the splitting members will be grasped and drawn out at the front to move the knife member through the full length of the box, 30 the knife portion 10 of the splitting member cutting a way through the mass of cement. This forms a passageway for the strip 12 which will be drawn through the passage formed by the knife until the advance end 35 of the strip 12 comes out through the slit 3 at the front end of the box, as shown in Fig. 8. It will be seen that the mass in each compartment is thus split into layers varying with the number of splitting members 40 for each compartment. As shown in the drawings there are two splitting members for each compartment and therefore it will be divided into three layers.

The pins 19 on which the box A rests will 45 now be withdrawn from supporting engagement with the box so that the box is free to be moved down. The box will now be forced down into telescopic relation to the base member by any suitable pressure means, 50 either hand or power, according to the size of the apparatus and the amount of pressure required until the upper edge of the box member A has passed below the upper face of the rail members 17, as shown in 55 Fig. 9. During the descent the knives 13 cut transversely through the several layers in the different compartments and through the paper strips 12, the knives at the bottom of the descent entering the transverse 60 grooves 22 in the rail members 17. Each layer will be cut into sections of the size desired for a single brick C, and all will be supported by the rail member 17. Thus 65 as illustrated in the drawings, each compartment will have three layers and each

layer of each compartment will be cut into three bricks thus making nine bricks in each compartment or twenty-seven for the entire apparatus, and each layer of bricks above the bottom one will be separated from the 70 brick beneath by a layer of the strip material 12.

The bricks should now be allowed to set. To provide convenient means by which this may be done and not interfere with the 75 immediate renewed operation of the apparatus, the rail members 17 are removable from the standards 16 as previously described. In order that they may be conveniently removed these rail members are 80 undercut at each end as shown in Figs. 3 and 9 forming flanges 23. This permits the rail members to be easily lifted off the standards. A convenient means of doing this would be to place a lifting bar under each 85 of the flanges 23 and a man standing at each end of the apparatus could grasp one end of each lifting bar in his hands and the two men together could easily lift the rails from the standards with the complete set of 90 bricks resting thereon and carry them to a suitable place where they will remain until the bricks are dry. Another set of rails can be mounted on the standards 16, the pins 19 being re-inserted to support the new set of 95 rail members and the box mounted thereon and the operation of filling the box and forming another set of bricks proceeded with. As many sets of rail members should be provided as necessary to allow the bricks, 100 already taken away, to become fully dried before the same rails are used over again.

What I claim is:

1. In an apparatus for the manufacture of bricks or other articles, a box to receive 105 a mass of cementitious material, a movable member adapted to move through the mass of cement to divide it into layers each equal in thickness to one of the articles to be produced, and means for drawing a strip of 110 sheet material into the passage cut by the movable member to form a partition between the said layers.

2. In an apparatus for the manufacture of bricks or other articles, a box to receive 115 a mass of cementitious material, a movable knife adapted to move horizontally through the mass of cement to divide it into layers equal in thickness to one of the articles to be produced, and a strip of sheet material drawn by the knife into the passage made by the knife to form a partition between the said layers, said box having a slit in one of its walls in alinement with the passage cut by the knife and through which the strip is drawn by the knife into the box and between the layers.

3. In an apparatus for the manufacture of bricks or other articles, a box to receive 130 a mass of cementitious material, a knife

adapted to move horizontally through the mass of cement to divide the mass into layers each equal in thickness to one of the articles to be produced and means for drawing a strip of sheet material into the passage cut by the knife to form a partition between the said layers.

4. In an apparatus for the manufacture of bricks or other articles, a box to receive a mass of cementitious material, a knife, means to move the knife horizontally through the mass of cement to divide the mass into layers equal in thickness to one of the articles to be produced and a strip of sheet material drawn by the knife into the passage cut by the knife to form a partition between the said layers, said box having slits in two opposite walls in alignment with the passage cut by the knife and through one of which the strip is drawn by the knife into the box and through the other of which the knife is moved when it draws the strip in.

5. In an apparatus for the manufacture of bricks, or other articles, a box to receive a mass of cementitious material, a knife movable horizontally through the mass of cement to divide the mass into layers equal in thickness to one of the articles to be produced, the side walls of the compartment containing the cementitious mass being formed with guideways for the knife, said knife being formed with an advance body portion equal in length to the length of the compartment containing the mass of material which is being divided, said body portion engaging with said guideways and being cut out to form a hollow center corresponding with the length and width of the compartment, the cutting portion being at one end of said opening and a strip of sheet material attached to the cutting end of the knife which is drawn into the passage cut by the knife to form a partition between the layers.

6. In an apparatus for the manufacture of bricks or other articles, a box to receive a mass of cementitious material, a movable splitting member adapted to be moved in such manner as to divide the cementitious mass in the box into layers, a member which supports the box during the dividing of the mass into layers, said box being open at the bottom and said support being of such di-

mensions that the box may be telescoped on to it, and knives mounted in the upper part of the box and extending transversely thereof, which, when the box is telescoped over the bed member will cut down through the several layers.

7. In an apparatus for the manufacture of bricks or other articles, a box to receive a mass of cementitious material, a movable member adapted to be moved in such manner as to divide the cementitious mass in the box into layers and insert a partition member of sheet material between the layers, a member which supports the box during the dividing of the mass into layers, said box being open at the bottom and said support being of such dimensions that the box may be telescoped over it, and knives mounted in the upper part of the box and extending transversely thereof, which, when the box is telescoped onto the bed member will cut down through the several layers and through the said sheet partition members.

8. The herein described method of forming a plurality of bricks or other articles consisting of moving a splitting member horizontally through a mass of cementitious material in a soft condition contained in a mold box of larger dimensions than the individual articles to be produced, inserting a strip of sheet material between the layers, then cutting vertically through the several layers and interposed sheet material partitions to divide the several layers into individual articles.

9. The herein described method of forming a plurality of bricks or other articles consisting of moving a splitting member horizontally through a mass of cementitious material in a soft condition contained in a mold box of larger dimensions than the individual articles to be produced and causing the splitting member to draw a strip of sheet material into the passage formed by the splitting member to form a partition member between the layers, then cutting vertically through the several layers and interposed sheet material partitions to divide the several layers into individual articles.

In testimony whereof I affix my signature.

ANTHONY M. ZOTTOLI.
